UNITED STATES PATENT OFFICE

2,445,532

RAZOR STROP STERILIZER

Versie R. Minton, New Orleans, La., assignor of
one-third to Frederick Irvin Dymond, New Or-
leans, La.

Application April 2, 1946, Serial No. 659,114

1 Claim. (Cl. 21—82)

1

The invention sufficiently described in the following specification that those versed in its art may understand its purposes, its functions and its mode of construction and manufacture, is also shown in the accompanying drawings which illustrate at least one form thereof, has for a primary object to provide means for the automatic sterilization of a razor strop after each use thereof.

Another object of the invention is to provide a sterilizing container and means therein for retracting thereinto a razor strop normally wound upon a roller in the container.

This invention has for another object to provide the combination of a razor strop case and disinfectant container.

A still further object of the invention is to provide a case for a razor strop having a slot through which the strop can be drawn against spring tension for use, the handle of the strop forming a closure for the slot.

Other features and advantages will become more readily apparent from the following description and the accompanying illustrative drawings in which:

Figure 1 is a perspective view of the invention,
Figure 2 is a transverse sectional view thereof,
and

Figure 3 is a sectional view taken on line 3—3 of Figure 2.

While one embodiment of the invention is illustrated in the above referred to drawings, it is to be understood that they are merely for the purpose of illustration and that various changes in construction may be resorted to in the course of manufacture in order that the invention may be utilized to the best advantage according to circumstances which may arise, without in any way departing from the spirit and intention of the device which is to be limited only in accordance with the appended claim. And while there is stated the primary field of utility of the invention it remains obvious that it may be employed in any other capacity wherein it may be found applicable.

In the accompanying drawings, 10 has reference to a perspective view of the complete invention which consists preferably of a cylindrical case 11 with removable end walls 12 and 13 held secured to the cylinder by a bolt 14 about which an inner cylinder 15 is rotatably mounted. This latter cylinder is divided into two sections by a disc 16 forming an inner compartment and an outer concentrically disposed compartment 18. A wooden block filler 19 is housed in the compart-

2

ment 18 and the inner compartment houses a clock spring 20, one end of which is secured to a pin 21 on the bolt 14 and the other end being fixed to the pin 22 on the inner surface of the cylinder 15.

Attached to the outer surface of cylinder 15 is a swivel or pin 23, to which is attached one end of a short chain 24 to the other end of which is attached the end 25 of a razor strop 26, which is a layer of leather 27 and a layer of canvas 28, the outer ends 29 and 30 of which are secured to the ends 31 and 32 of a leather loop 33, upon which loop is secured the bar 34 of a plate 35, which forms a closure for the slot 36 provided in the cylinder 11 through which the strop 26 is adapted to move forward and back from and into the cylinder 11. The plate 35 supports the handle 37 upon it in fixed position.

It is to be noted that the bolt 14 (which also forms a shaft upon which the cylinder 15 is rotatable) has its threaded end 40 projecting through a bore 41 in wall 12 and is held by a nut 42. The end 43 of the bolt is threaded into the wall 13 of the device. Also threaded upon the end 43 of the bolt is a nut 44 which forms a thrust bearing against the block 19 whereby the cylinder 15 will be held in position for the strop 26 to align with slot 36.

Attached to one side 46 of the cylinder 11 by means of flanges 47 and the screws 49 is a container 50 for a disinfectant, the fumes from which raise through apertures 51 in the said cylinder 11 and completely fill the case and surrounding the strop therein, adequate room 52 around the wound strop permitting the fumes to penetrate between the convolutions of the strop. A gasket 53 is seated between the flanges 47 and the case 11, to prevent leakage of the disinfectant or its fumes. It is understood that the plate 35 will be provided with a rubber or other gasket (not shown) on its inner side whereby escape of fumes will be effectually prevented when the strop is enclosed in the case.

Fixed on the side 54 of the cylinder 11 is a bracket channel member 55, the flanges 56 and 57 of which may be either welded or otherwise secured to the cylinder. This member 55 is open at both ends 58 and 59 whereby it may be attached to the rear hinge under the right 50 arm of a barber's chair for the convenience of a barber using the strop.

While the mechanical construction of the above described invention has been disclosed to a sufficient extent to make the same clearly understood and while certain functions of the ele-

ments thereof are obvious even if not specifically mentioned, still it is to be understood that there may be other functions which for reasons of brevity have not been gone into more fully because it is thought unnecessary for further clarification due to the fact that the appended claim is drawn to its construction which pretty well covers the subject matter thereof, although applicant retains the right to further amplify the claim upon a full disclosure of the art.

From the foregoing specification it will become apparent that the invention disclosed will adequately accomplish the functions for which it has been designed and in an economical manner and that its simplicity, accuracy and ease of operation are such as to provide a relatively inexpensive device considering what it will accomplish and that it will find an important place in the art to which it appertains when once placed on the market.

It is thought that persons skilled in the art to which the invention relates will be able to obtain a clear understanding of the invention after considering the description in connection with the drawings. Therefore, a more lengthy description is regarded as unnecessary.

Changes in shape, size and rearrangement of details and parts such as come within the purview of the invention claimed may be resorted to, in actual practice, if desired.

Having now described the invention, that which

is claimed to be new and desired to be procured by Letters Patent is:

A razor strop sterilizer comprising a cylindrical case and inwardly extending peripherally flanged end closures removably supported thereon and overlying the ends thereof, an axially disposed bolt extending through said case and end closures, a cylindrical block fixed upon said bolt, a cylinder rotatably mounted about said cylindrical block, a razor strop secured to and wound about said cylinder, a clock-type spring fixed at one end to said bolt and fixed at its opposite end to said cylinder for resiliently winding up the strop upon said cylinder, said case being longitudinally slotted, a handle plate attached to the outer end of said razor strop adapted to extend through said slot and to be connected with said strop for sealing said slot when the strop is rolled up within said case, and a sterilizer receptacle at the bottom of said case having perforated means between the same and said case.
